UNITED STATES PATENT OFFICE.

JOHN KRALUND, OF NEW YORK, N. Y., AND MARCUS STERN, OF TOLEDO, OHIO,
ASSIGNORS TO DOEHLER DIE-CASTING COMPANY, OF BROOKLYN, NEW YORK,
A CORPORATION OF NEW YORK.

CASTING APPARATUS.

1,292,484.

Specification of Letters Patent. Patented Jan. 28, 1919.

Application filed August 10, 1917. Serial No. 185,429.

To all whom it may concern:

Be it known that we, JOHN KRALUND and MARCUS STERN, both citizens of the United States, residing, respectively, in the borough 5 of Brooklyn, city of New York, county of Kings, and State of New York, and at Toledo, in the county of Lucas and State of Ohio, have jointly invented certain new and useful Improvements in Casting Apparatus, 10 of which the following is a specification, reference being had therein to the accompanying drawings, which form a part thereof.

Our invention relates to casting apparatus and more particularly to a type thereof in 15 which molten metal is forced from a cylinder into a metal die in making pressure die castings.

An apparatus made in accordance with our invention is specially adapted for making 20 castings of the lower fusion white metal alloys, and is automatic to the extent that the rate of flow of the metal into the die, the force or pressure exerted upon the metal during the casting operation and the return 25 of the plunger to normal to recharge the pressure cylinder, with the incidental agitation of the molten mass in the melting pot, is mechanically controlled. This permits the production of a large number of castings 30 under identical pressure conditions; avoids those variations in castings resulting from the impossibility of a man always applying the same force to the plunger or operating it at the same rate of speed and gives greater 35 capacity to the machine as compared with hand operated machines.

In a machine made in accordance with our invention, wherein the metal is forced from the pressure cylinder by means of a mechanism 40 utilizing fluid pressure, such as compressed air or steam, the range of the sizes of the casting which may be produced is very much increased, as compared with hand operated machines, and the working conditions 45 about the machine are the same, irrespective of the size, or weight, of the casting being made. The main advantage secured by a machine made in accordance with our invention, however, is the elimination of 50 man-power in actuating the machine while preserving all of those conditions which are essential to secure a proper and rapid filling of the mold and uniformity in the density of the metal in succeeding castings.

It is essential in a machine made in accordance with our invention to start the plunger at a high speed and decrease the movement thereof so as to gradually increase the pressure upon the metal as the die is being filled and maintain this pressure 60 until the metal has solidified sufficiently to prevent back flow from the die into the pressure pot or cylinder. In this manner, the operator has merely to actuate a valve controlling the flow of the fluid to the power 65 cylinder, the variance of the pressure upon the metal flowing into, and contained within, the mold or die, resulting from the adjustment of the machine and not being dependent upon the operator thereof. It is preferable to use a double acting piston, with a valve so constructed as to cause the actuation thereof to open an exhaust port communicating with one side of said piston when the inlet port communicating with the other side 70 thereof, is opened.

By utilizing an elastic fluid pressure, we are enabled to not only secure the desired rapid movement of the plunger with the variable pressure conditions in the pressure cylinder 80 above referred to, but to secure a variable thrust of the plunger in proportion to the volume of metal required to fill any mold, and an automatic increase in the power exerted upon the plunger in proportion to the 85 increase in the size and weight of the casting.

In the accompanying drawings, we have illustrated our invention in connection with a well known type of casting apparatus omitting therefrom a showing of the die support and rigging, such being immaterial to a full understanding of the invention, and being well known to those skilled in the art.

The invention consists primarily in a casting apparatus embodying therein a melting pot, a pressure cylinder communicating therewith, a plunger mounted in said pressure cylinder, an actuating lever, one arm of which is operative upon said plunger, a power cylinder, a piston mounted therein, 95 operative connections between said piston and the other arm of said lever, connections between said power cylinder and a source of fluid under pressure, and a valve mechanism controlling the flow of said fluid to and from said power cylinder, and in such other novel features of construction and combination of parts, as are hereinafter set forth and de-

scribed and more particularly pointed out in the claims hereto appended.

Referring to the drawings:

Figure 1 is an end view of an apparatus 5 embodying therein our invention;

Fig. 2 is a side view thereof partly in section;

Fig. 3 is an end view of the controlling valve;

10 Fig. 4 is a section on the line 4—4 of Fig. 3 with the valve block set for restoring the parts to their normal operative positions;

Fig. 5 is a similar section with the valve block set in a manner to cause the actuation 15 of the plunger to inject metal into the mold or die; and

Fig. 6 is a cross section of the valve key.

Like letters refer to like parts throughout the several views.

20 In the embodiment of our invention shown in the drawings, *a* indicates a furnace casting having mounted within same a melting pot *a'* adapted to contain molten metal heated from the furnace. Said melting pot has 25 a suitable closure top *a''*. Supported from, and positioned within, the melting pot *a'* is a pressure cylinder, *b*, having an outlet nozzle *b'* and ways *b''* suitably spaced apart and projecting from the open end thereof.

30 Slidably mounted in said cylinder *b* is a piston *c* having an undercut end *c'* so that when the piston is withdrawn from the bore of the cylinder and supported entirely by the ways *b''* metal may flow from the central

35 portion of the melting pot into said cylinder. The construction and arrangement heretofore described is old and well known in this art, as is the rigging for supporting the die with the ingate thereon adjacent the 40 nozzle *b'*, for which reason said rigging is not illustrated in the accompanying drawings.

Heretofore the piston or plunger *c* has been manually actuated for forcing the 45 metal from the cylinder *b* into the mold or die, by means of a hand lever.

In our present invention, this piston is actuated by fluid pressure, such as compressed air or steam. In the form of the 50 invention shown, this mechanism comprises a power cylinder *d* having mounted therein a piston *e* operatively connected with the piston or plunger *c*. In order to utilize fluid pressure for imparting movement to 55 the plunger in both directions, we use a double acting piston, mounted in a cylinder closed at both ends and provide means for controlling the flow of the fluid under pressure alternately upon opposite sides of said 60 piston and means whereby the fluid upon one side of said piston will be automatically exhausted when the fluid is admitted to the other side thereof. Connected with the stem *e'* of the piston *e* is a cross head *f* mounted 65 upon suitable guide rods *f'*. Pivottally

mounted in suitable bearings carried by the pressure cylinder *b* is a lever *g*, one arm of which is connected with the plunger or piston *c* in a manner to afford lost motion to compensate for the arc described by said lever, and the other arm of which is connected with the cross head *f* by means of the connecting rod *h* pivotally connected to said other arm of said lever, and to said cross head respectively. 75

The lever *g* is so formed that when the piston *c* is in the uppermost position, as shown in Fig. 2, the point of pivotal connection between the connecting rod *h* and the lever *g* will be off center and the piston or plunger *c* will be entirely withdrawn from the cylinder *b*, so as to insure a proper starting of the piston or plunger, while at the same time insuring a low starting leverage with a gradual increase in this leverage 85 as the piston *c* descends. In this manner, we not only secure the maximum applied pressure in making a casting, but the power applied to the plunger will be increased to adapt the mechanism to the making of castings of different sizes. Where a large casting is made it is not only necessary to force a larger quantity of metal from the pressure cylinder *b* but the final pressure upon the molten metal in the die must be greater to 95 secure the desired compaction of this metal.

The means for controlling the flow of the fluid to the cylinder *d* is so constructed as to insure a slow return movement of the piston *e* and avoid the splashing of the 100 molten metal about the melting pot *a'*.

Leading to any desired source of power of fluid under pressure, is a pipe line *i* having arranged therein a drain cock *i'* and a controlling valve *i''*. Communicating with 105 the pipe line *i* is a pressure gage *i'''*.

The means for controlling the flow of the fluid from the pipe line *i*, in the form of the invention shown, consists of a valve mechanism having a casing *j* provided with 110 an intake port *j'* with which the pipe line *i* communicates and two outlet ports *j''—j'''*, one of which communicates through the pipe *j''* with one end of the cylinder *d* and the other of which communicates through 115 the pipe *j'''* with the other end of said cylinder, said cylinder being provided with ports suitably formed to insure the proper delivery of the fluid passing therethrough, to or from said cylinder. The ports *j''—j'''* are 120 arranged in substantially the same plane, the port *j'* being off-set in relation to said other ports in said casing *j*. Rotatably mounted in the casing *j* is a valve key *k* having therein a bore *k'* opening outwardly 125 thereof into atmosphere or any other point for discharge of the fluid. Said key has therein a port *k''* leading from said bore and adapted to communicate successively with the ports *j''—j'''*. Said key is also pro- 130

vided with a circumferentially extending channel m adapted at all times to be in communication with the port j' . Leading from the channel m is a passage n communicating with a port n' adapted to register with the port j^2 , a narrow, shallow channel n^2 extending from said port circumferentially about the key to a position where, when the port k^2 is in register with the port j^2 , said channel n^2 will be in communication with the port j^3 .

The valve key k is tapered, as shown, being acted upon by a spring o encircling a rod o' carried by the key k and acting against a spring seat o^2 , in a manner to normally draw said key within its casing and insure an automatic readjustment of the valve to its seat, to compensate for any possible wear. The end of the said key is provided with an angular portion p adapted to be engaged by a recess in the operating handle p' .

The valve casing j is provided with a stop pin p^2 adapted to engage portions of the operating handle p' extending upon opposite sides of the axis of the key k and limit the oscillatory movement of said lever in both directions.

The operation of the herein described apparatus is substantially as follows:

Normally the piston e will be in its uppermost position, the cross head f being drawn upwardly in a manner to so position the lever g as to bring the plunger or piston c entirely without the cylinder b and within the ways b^2 . When the parts are in this position, the metal may readily flow into the cylinder from a point in the melting pot, intermediate the uppermost and lowermost strata of the molten metal therein, thus insuring delivery of clean metal to the cylinder.

When the parts are in this position, the extension n^2 of the port n' is in communication with the port j^3 , delivering fluid under pressure to the cylinder upon one side of the piston e , and the port k^2 is in communication with the port j^2 placing the cylinder d upon the other side of the piston e in communication with atmosphere through the bore k' .

When the machine is properly set for casting, the key k is turned by means of the handle p' bringing the port n' in register with the port j^2 , and the port k^2 in register with port j^3 , thus delivering the fluid pressure upon the upper side of the piston e while presenting a clear passage to atmosphere from the lower side of said piston, to permit the exhausting of the fluid pressure therein. When the lever p' has been actuated to an extent to bring the various co-operating ports into full register, the end thereof projecting beyond the key will engage the stop pin p^2 .

As the fluid under pressure enters the up-

per portion of the cylinder d above the piston e , the cross head f will descend at uniform speed if the power be applied with one movement of the key, or with a gradual acceleration, if the movement of the key be gradual. The control of the force with which the metal is forced from the pressure cylinder b is not, however, dependent upon a variable piston speed but results solely from the construction of the apparatus, or of the connections intermediate said power piston e and the piston or plunger c .

As the cross head f begins to descend, the leverage at which the connecting rod h acts upon the lever g , will be the minimum for which the machine is set, the construction of this lever g being such that the movement of the plunger or piston c with its maximum movement, will be gradually accelerated during the first portion of its stroke and gradually retarded toward the end of its stroke. As the arm of the lever g to which the connecting rod h is connected, swings outwardly and downwardly, the leverage at which the said connecting rod acts, will gradually increase reaching its maximum toward the end of the effective stroke of the said piston c , which stroke will vary in length, according to the volume of metal required to be forced from the pot to fill the die. If this volume of metal be small, the movement of the piston will be proportionately small, and the final pressure will be low, as compared with the pressure developed upon a longer movement of the piston or plunger c , or longer oscillation of the lever g . If, however, a large casting is to be made necessitating the forcing of a greater volume of the metal from the pressure cylinder, there will be a longer movement of the piston e and greater oscillation of the lever g with a resultant gradual increase in the speed at which the plunger c will be advanced in its cylinder and the pressure exerted upon the metal within the die cavity toward the end of the stroke will be proportionately increased. Hence, the rapid charging of the die and the development of pressure upon the metal therein, when the die or mold is completely filled, proportionate to the needs of any particular casting, is insured. It will be observed that the machine automatically adjusts itself to any size of casting to be made, irrespective of the manner in which the key k may be actuated or of the manner of applying the pressure to the piston e .

It is desired to point out that the filling of the mold limits the movement of the piston or plunger c and also that of the piston e . Hence, the piston e is an automatically controlled, variably movable piston, adapting the machine for the production of castings of varying sizes.

After the piston e has reached the limit

of its downward stroke, a return of the valve key *k* to normal is delayed momentarily to maintain pressure upon the metal in the die cavity until initial solidification has occurred, or until any tendency of the metal to flow from the die through the ingate thereof is passed. If a sprue cutter be used, the pressure is maintained until said sprue cutter has been actuated.

10 When the casting has been thus made, the key *k* is restored to its former position as defined by the engagement of the handle *p'* with the stop pin *p*², bringing the ports in the position shown in Fig. 5 of the accompanying drawings. When the ports are in this position, the upper portion of the cylinder *d* will exhaust through the bore *k'* while the compressed fluid, in reduced volume, will be admitted below said piston in 20 a manner to gradually restore the parts to the normal position, as shown in Fig. 2.

In Fig. 2, the relation of parts is such that the piston *e* is just about to descend to force the metal from the cylinder *d*.

25 The gradual return of the piston or plunger *c* to normal prevents excessive splashing of the metal and does not reduce the capacity of the machine since it is during this interval that a casting or castings are drawn 30 from the die.

In a machine made in accordance with our invention, we not only secure the requisite variable pressure within the pressure cylinder *b* with a constant power applied to the 35 power cylinder, and the maximum application of this pressure when the mold cavity is completely filled, but pressure conditions with all castings made will be uniform with a resultant uniformity in the product from 40 any die.

It is not our intention to limit the invention to the precise details of construction shown in the accompanying drawings, it being apparent that such may be varied without departing from the spirit and scope of 45 the invention.

Having described the invention, what we claim as new and desire to have protected by Letters Patent is:—

50 1. A casting apparatus embodying therein in a melting pot, a pressure cylinder communicating therewith, a plunger mounted in said cylinder, an actuating lever, one arm of which is operative upon said plunger, a power cylinder, a piston mounted therein, operative connections between said piston and the other arm of said lever, connections between said power cylinder and a source of fluid under pressure, and a valve mechanism 55 controlling the flow of said fluid to and from said power cylinder.

60 2. A casting apparatus embodying therein in a pressure cylinder adapted to receive molten metal and means forcing the molten 65 metal from said cylinder comprising a

power cylinder, means controlling the flow of fluid under pressure to and from said power cylinder, a plunger mounted in said pressure cylinder, a piston mounted in said power cylinder, and connections between 70 said piston and said plunger such that a constant speed of and power exerted by said piston will cause a variable speed of, and a gradually increased power exerted by, said plunger in forcing metal from said pressure 75 cylinder.

3. A casting apparatus embodying therein a melting pot, a pressure cylinder communicating therewith, a plunger mounted in said cylinder, an actuating lever, one arm of 80 which is operative upon said plunger, a power cylinder, a double acting piston mounted therein, operative connections between said piston and the other arm of said lever, connections between the opposite ends 85 of said power cylinder and the source of fluid under pressure, and a valve mechanism adapted to alternately connect the opposite sides of said piston with said source of fluid supply and simultaneously exhaust the fluid from the other side of said piston from that into which the fluid is permitted to flow. 90

4. A casting apparatus embodying therein in a melting pot, a pressure cylinder communicating therewith, a plunger mounted in 95 said cylinder, an actuating lever, one arm of which is operative upon said plunger, a power cylinder, a double acting piston mounted therein, operative connections between said piston and the other arm of said lever, connections between the opposite ends 100 of said power cylinder and the source of fluid under pressure, and a variable operative valve mechanism adapted to alternately connect the opposite sides of 105 said piston with said source of fluid supply and simultaneously exhaust the fluid from the other side of said piston from that into which the fluid is permitted to flow.

5. A casting apparatus embodying therein 110 a pressure cylinder adapted to receive molten metal and means forcing the molten metal from said cylinder comprising a power cylinder, a plunger mounted in said pressure cylinder, a double acting piston mounted in said power cylinder, a valve mechanism adapted to alternately permit fluid under pressure to flow to opposite sides of said piston and simultaneously exhaust the fluid from the other side of said piston from that into which the fluid is permitted to flow, and connections between said piston and said plunger, such that a constant speed of, and power exerted by, said piston will cause a variable speed of, and a gradually increased 120 power exerted by, said plunger in forcing metal from said pressure cylinder.

6. A casting apparatus embodying therein 125 a pressure cylinder adapted to receive molten metal and means forcing the molten 130

metal from said cylinder comprising a power cylinder, a plunger mounted in said pressure cylinder, a double acting piston mounted in said power cylinder, a variably operative valve mechanism adapted to alternately permit fluid under pressure to flow to opposite sides of said piston and simultaneously exhaust the fluid from the other side of said piston from that into which the 5 fluid is permitted to flow, and connections between said piston and said plunger such that a constant speed of and power exerted by said piston will cause a variable speed of, and a gradually increased power exerted by, 10 said plunger in forcing metal from said pressure cylinder.

7. In a casting apparatus, the combination of a pressure cylinder adapted to receive molten metal, a plunger therein, an actuating 15 lever, one arm of which is operative upon said plunger, a reciprocating member,

guiding means for the same, a link pivotally connecting said member with the other arm of said lever, and power means for reciprocating said member, said lever and link 25 being so arranged that the leverage exerted upon said plunger increases during the operative stroke of said plunger.

In witness whereof, we hereunto affix our signatures in the presence of two subscribed 30 witnesses, this 23rd day of July, 1917, as to KRALUND, and this 26th day of July, 1917, as to STERN.
